(57) **CLAIM**

The ornamental design for a motorcycle display plate, as shown and described.

DESCRIPTION

The present invention relates to an ornamental design for a motorcycle display plate for the display of company logos.

FIG. 1 is a perspective view showing the design of the motorcycle display plate.

FIG. 2 is a top view showing the design of the motorcycle display plate.

FIG. 3 is a front view showing the design of the motorcycle display plate.

FIG. 4 is a first end view showing the design of the motorcycle display plate.

FIG. 5 is a second end view showing the design of the motorcycle display plate.

FIG. 6 is a bottom view showing the design of the motorcycle display plate; and,

FIG. 7 is a rear view showing the design of the motorcycle display plate.

The broken lines illustrate environmental features and structure that form no part of the claimed design.
